UNITED STATES PATENT OFFICE.

FREDERICK W. DRESSEL, OF NEW YORK, N. Y., ASSIGNOR TO THE DRESSEL RAILWAY
LAMP WORKS, A CORPORATION OF NEW YORK.

HEADLIGHT.

1,221,007.

Specification of Letters Patent. Patented Mar. 27, 1917.

Application filed January 2, 1915. Serial No. 188.

To all whom it may concern:

Be it known that I, FREDERICK W. DRESSEL, a citizen of the United States, residing at the city of New York, borough of Manhattan, in the county and State of New York, have invented certain new and useful Improvements in Headlights, of which the following is a full, clear, and exact specification.

10 My invention relates to improvements in lanterns, and the same has for its object a simple, efficient, and reliable apparatus by which a beam of light of great intensity may be produced and projected.

15 Further, said invention has for its object to provide a lantern in which the reflector may be readily adjusted to bring the flame of the lamp into the exact focal point of the reflector whereby to obtain the maximum 20 efficiency of the lamp.

Further, said invention has for its object to provide a lantern having the reflector composed of a fixed portion in which the lamp is located, and a movable portion adjustable relative to said fixed portion, whereby to permit of the reflector being brought into proper focal position relative to the reflector as a whole.

Further, said invention has for its object 30 to provide a reflector for headlights which may be readily adjusted to permit of the use of different types of electric lights or of lamps employing burners producing or burning with flames of different sizes or shapes.

To the attainment of the aforesaid objects and ends, my invention consists in the novel details of construction, and in the combination, connection, and arrangement of 40 parts hereinafter more fully described and then pointed out in the claims.

In the accompanying drawings Figure 1 is a side view of a headlight constructed according to and embodying my said invention; the door of the lantern being removed in order to expose the interior thereof;

Fig. 2 is an enlarged top view showing the rear portion of the reflector and a lamp in position therein;

50 Fig. 3 is a transverse section taken on the line 3—3 of Fig. 2, and

Fig. 4 is a central longitudinal section taken on the line 4—4 of Fig. 2.

In said drawings 10 designates the lantern 55 casing within which is supported an oil

font 11, and a burner 12. 13 denotes the reflector, consisting of a parabolic forward section 14 having a cylindrical rear end 15. The cylindrical portion 15 and the rear end of the reflector 14 are cut out at their tops 60 and bottoms to receive the lamp burner 12 and chimney 16. The parabolic section 14 is rigidly secured within the lantern 10 and has its inner surface silvered or otherwise suitably prepared to render the same efficient as a reflecting surface. 65

Upon the cylindrical section 15 extending from the rear of the parabolic portion 14 is disposed an adjustable back comprising a cylindrical section 17 which fits snugly upon 70 the cylindrical section 15, and is provided with diagonal slots 18, 18 through which extend screws 19, 19 having their heads disposed upon the inner side of the cylindrical section 15. Upon the outer threaded ends of 75 said screws 19 are arranged thumb nuts 20.

The rear end of the cylindrical section 17 is flared outwardly and has its edge formed into a horizontal rim portion 22. 23 denotes a concave back provided with a tapering rim 23^a having its rear edge bent inwardly to form a bead 23^b which embraces the edge of the back 23, and is received by the rim portion 22 of the cylindrical section 17. 24 denotes an annular split collar having inwardly-extending flanges 24^a, 24^b which embrace the rim portion 22 and the bead 23^b. The forward edge of the tapering rim 23^a is turned inwardly to form a flange 23^c which serves to retain the spherical concave reflector-mirror 25 duly in position upon the back 23. 85 90

The annular collar 24 is provided adjacent to its separated ends with upwardly extending lugs 24^a, 24^b, through which passes a 95 screw 26 provided with a nut 27 whereby to secure said collar and related parts duly in position upon the cylindrical section 17.

It will be understood, of course, that the parabolic reflector section 14, as well as the lamp comprising the burner 12 and chimney 16 are rigid relative to the casing. In order to bring the flame of the lamp into the exact focal point of the reflector comprising the parabolic section 14 and back 23, it merely 100 becomes necessary to release the thumb screws 20 which will permit of the cylindrical section 17 of the back being rotated slightly, and as the same is rotated it will 105 be caused to move forward or backward rel- 110

ative to the parabolic section 14. As the position of the rear reflector 25 can be approximately adjusted in advance it requires but a very slight adjustment to bring the flame 5 into the exact focal point of the reflector as determined by photometer and this can be accomplished by rotating the back and moving the same slightly forward or backward as required. When the back has been 10 adjusted to its proper position the same may be firmly and rigidly secured to its place by means of the thumb nuts 20, 20. It is to be noted particularly that although the amount of adjustment accorded the adjustable 15 back section is limited it is nevertheless sufficient since the movement of 1/32 of an inch may increase the candle power of a lamp, for example, from 2700 to 3000—the maximum efficiency of the lamp. In other instances the candle power may be increased as much as 600 candle power or more, which would otherwise be lost owing to imperfect adjustment.

Having thus described my invention, what 25 I claim and desire to secure by Letters Patent is:—

1. In a headlight, the combination with a parabolic reflector, of a source of light fixed with respect thereto, a reflecting member 30 in rear of said source of light and of said parabolic reflector, and means adjustably securing said reflecting member to said parabolic reflector for movement toward and away from said source of light, substantially as specified.

2. In a headlight, the combination with a parabolic reflector having an annular portion extending from the rear thereof, of a source of light fixed with respect to said 40 reflector, and a reflecting member in rear of said source of light and adjustably supported upon the annular portion of said parabolic reflector for movement toward and away from said source of light, substantially as specified.

3. In a headlight, the combination with a parabolic reflector having a horizontally-disposed, annular portion extending from the rear thereof, of a source of light fixed with 50 respect to said reflector, and a reflecting member in rear of said source of light and adjustably supported upon the annular portion of said parabolic reflector for movement toward and away from said source of light, substantially as specified.

4. In a headlight, the combination with a reflector having a rearwardly extending annular portion, of a source of light fixed with

respect to said reflector, a member having an annular portion engaging said rearwardly extending annular portion, said member being adjustable with respect to said source of light, and a reflecting member carried by said member, substantially as specified. 60 65

5. In a headlight, the combination with a reflector having a rearwardly extending portion, of a source of light fixed with respect to said reflector, a member adjustably mounted upon said rearwardly extending portion and having a rim at the rear thereof, and a reflecting member supported within said rim, substantially as specified. 70

6. In a headlight, the combination with a reflector having a rearwardly extending portion, of a source of light fixed with respect to said reflector, a member adjustably mounted upon said rearwardly extending portion and having a horizontally-disposed rim at the rear thereof, a back supported within said rim, and a reflecting member secured to said back, substantially as specified. 75 80

7. In a headlight, the combination with a reflector having a rearwardly-extending portion, of a source of light fixed with respect to said reflector, a member adjustably mounted upon said rearwardly extending portion and having a horizontally-disposed rim at the rear thereof, a back supported within said rim, a reflecting member secured to said back, and means for removably holding the back in position within said rim, substantially as specified. 85

8. In a headlight, the combination with a reflector having a rearwardly extending portion, of a source of light fixed with respect to said reflector, a member adjustably mounted upon said rearwardly extending portion having a rearwardly-extending, outwardly flared portion and a horizontally-disposed rim at the rear of said flared portion, a back supported within said rim and having a tapering portion engaging the flared portion of said member, a reflecting member carried by said back, and means to hold said back in position within said rim, substantially as specified. 95 100 105

Signed at the city of New York, in the county and State of New York, this 16th day of July, one thousand nine hundred and fourteen.

FREDERICK W. DRESSEL.
